UNITED STATES PATENT OFFICE.

FRANK J. SPRING, OF READING, PENNSYLVANIA.

DOOR-CHECK.

1,052,019.

Specification of Letters Patent.

Patented Feb. 4, 1913.

Application filed May 16, 1912. Serial No. 697,606.

To all whom it may concern:

Be it known that I, FRANK J. SPRING, a citizen of the United States, residing at Reading, in the county of Berks and State 5 of Pennsylvania, have invented certain new and useful Improvements in Door-Checks, of which the following is a specification.

This invention relates to improvements in door checks and the object is to provide a 10 device of simple construction that may be applied with equal facility to either a right or left hand door, and one which may be changed from a right to a left hand door action without removing or changing any 15 of the parts, the device being free to act in either direction and being provided with means for attaching it to the door jamb so that it will be in position for either movement of the door.

20 The device is so constructed that the door may be opened with a minimum of effort and the return of the door is substantially uniform during almost the whole of its closing path.

25 The invention is more fully described in the following specification and clearly illustrated in the accompanying drawing, in which:—

Figure 1 is a plan view, showing my device in position on a closed door, with the 30 open position shown dotted. Fig. 2 is a central longitudinal section of the casing. Fig. 3 is a detail of the by-pass regulating screw. Fig. 4 is a detail of the roller bearing.

35 The numeral 1 designates a door and 2 the jamb.

3 designates the check casing which has a cover 4 formed with a securing plate 5 40 by means of which it is secured to the door.

The device is provided with the usual arm 7 for connection to the door jamb and in this case I form this arm with a ball and socket joint at its connection with the check 45 operating arm 8. This arm 8 is secured to a vertical shaft 9 located in the check casing, passing through the cover, and formed at its lower extremity with an anti-friction surface 10 adapted to rest in a suitable cup-like depression 11 in the bottom of the casing, so as to reduce the friction at this point 50 to a minimum. Any other simple ball bearing may be employed if desired. Inside the casing, and secured to the shaft 9 by means 55 of a pin 12 is located a movable or rotary

cylindrical member 15, adapted to turn with the shaft. This member is formed with one or more inclined faces, on its lower edge, and at its lowermost point it is provided with suitable anti-friction rollers 17. In 60 the casing, below this rotatable member, I secure a like cylindrical member 18, adapted to move only in a vertical direction in the casing, being guided by one or more guide strips 19, and formed at its upper edge with 65 inclined surfaces corresponding with those on the upper member, and against which the rollers 17 will bear when the upper member is rotated. These members 15 and 18 are hollow and the member 18 is provided with 70 a valve 20 to permit the passage of the liquid 21, as is usual in this type of check. This member 18 is backed by a spring 22 which serves to keep it in normal position 75 against the upper member, and a by-pass 23 is formed in the wall thereof, provided with a regulating screw 24.

With the parts in position as shown, the closing of the door will cause the shaft 9 to turn in the casing and to turn with it the 80 upper member 15; this movement will force the lower member 18 down on the guides, through the action of the rollers on the inclined surfaces; as it is thus moved, the liquid in the casing will be forced slowly 85 through the by-pass 23 and permit the slow and regular closing of the door. When the door is fully closed, the liquid will be inside the lower member, which member will be in the lower end of the casing, and the rollers 90 will be at the top of the inclined surfaces on said member. The opening of the door, will, as is usual, turn the arm and shaft 9 in the opposite direction, and permit the lower member 18, through the action of the spring 95 22, to ride up with relation to the upper member, and when this movement begins, the valve 20 will open and permit the liquid to pass out easily, thus permitting the door 100 to be opened without undue effort. The only resistance in opening the door, is the usual closing spring 26, which, in this case is inclosed in a tubular member secured to the operating arm at its jointure with the 105 jamb connecting arm 7. The spring is joined to the casing in any suitable manner, so that when the door opens, as shown in Fig. 1, the spring is drawn into tension so that when the door is released it will act to close it. This closing is slightly aided how- 110

ever by the action of the spring in the check casing whose action is at all times opposed to that on the operating arm.

It is evident that to apply my device to a left hand door it is only necessary to place the operating arm on the opposite side of the casing from that shown in Fig. 1 and secure the arm 7 to the jamb on that side. Inasmuch as the parts are free to swing 10 around into either position, it is evident that it may be applied with equal ease in either right or left hand operating position.

Having thus fully described my invention, I claim:

15 1. In a reversible door check and closer, a casing, a cover therefor, a rotating shaft therein, a cup like receptacle centrally located in the bottom of the casing forming a bearing for the shaft, a check operating arm 20 connected to the shaft, a tension spring connected to the casing cover, a jamb engaging arm connected with the check operating arm and adapted to be swung from one side of the casing to the other, whereby to hold said 25 check operating arm in position for right or left hand action, a rotating cylindrical member within the casing and secured to the shaft, said member having an inclined lower edge, a roller secured to the lowermost point 30 of said member, a second cylindrical member having its upper edge inclined and adapted to be engaged by the rollers and to be moved vertically in a downward direction by the rotary action of the upper member, guides 35 for the lower member, said member having a valve in its lower wall and a by-pass in its vertical wall, a regulating screw formed with a slotted bearing point located in the by-pass and a spring within the casing to 40 keep the said cylindrical members normally in contact with each other.

2. In a reversible door check and closer the combination of a cylindrical casing formed with a cup like receptacle in its bottom, a rotary shaft seated therein, a reversible operating arm connected to the shaft, a cylindrical member rotatably mounted on the shaft and located within the casing, said

member having its lower face inclined, a pair of rollers secured to the lowermost point of said inclined faces, vertical guides on the inner wall of the casing, a vertically movable cylindrical member adapted to move along said guides, said member having its upper face inclined and adapted for engagement constantly with the said rollers whereby the rotation of the upper cylindrical member will move the lower cylindrical member in one direction, a spring located between the bottom of the casing and the lower member to move the said member in the opposite direction, a valve in the bottom of the lower member, a vertical slot in the outer wall of said lower member to serve as a liquid bypass and a regulating screw 65 formed with a slotted bearing point, passing through the casing wall and adapted to regulate the passage of liquid through the bypass.

3. In a reversible door check and closer 70 the combination of a casing, a cover therefor provided with means for securing it to the door, a reversible operating arm having means for securing it to the door jamb for either right or left hand action, a pair of 75 cylindrical cams in the casing, one of which is mounted for rotary movement within the casing and the other for vertical movement therein, means on the rotary cam for moving the vertically movable cam in a downwardly 80 direction, a spring for moving said vertically movable cam in an upwardly direction, a shaft to which the rotary cam is secured, a bearing in the bottom of the casing for the shaft, a valve in the vertically movable cam, 85 guides in the inner wall of the casing for said vertically movable cam, a by-pass in said vertically movable cam and a slotted screw in the by-pass to regulate the flow of liquid therethrough.

In testimony whereof I affix my signature in presence of two witnesses.

FRANK J. SPRING.
